UNITED STATES PATENT OFFICE.

GEO. R. COMSTOCK, OF MANHEIM, NEW YORK.

CARRIAGE-SEAT.

Specification of Letters Patent No. 12,273, dated January 23, 1855.

To all whom it may concern:

Be it known that I, GEORGE R. COMSTOCK, of Manheim, Herkimer county, State of New York, have invented a new and Improved 5 Method of Constructing the Bodies and the Seats of Two-Wheeled Carriages, which I call "Comstock's Adjustable Carriage-Seat," of which the following specification, with the drawings appended hereto as part of the 10 same, is a full and accurate description.

It is well known that in the use of all two wheeled carriages, as at present constructed, if the position of the seat be such as to adapt advantageously the pressure of the 15 weight of its load upon the horse through the shafts, when the carriage is standing or moving upon level ground, whenever the ground varies from that level, the pressure is varied upon the shafts so as to affect disadvantageously the draft of the horse, that is 20 when the carriage is going up ascending ground, the load will be thrown behind the perpendicular and when going down descending ground, before the perpendicular, 25 in the first case taking part of the weight off from, and in the second case adding to the weight from the horse. Now it is to remedy this difficulty and to effect as nearly 30 as may be an equalization of the pressure upon the horse that my invention is intended to effect.

Figure 1 represents a perspective view of a gig body and seat made according to my plan. Fig. 2 a diagram to show the effect of 35 shifting the seat in different positions of the vehicle.

A, A, A, A, shows an ordinary gig body, the seat or upper body B, B, being made 40 separate from the body, and attached to it by loops underneath it which slide upon rods, the ends of which are shown in the drawing at C C, and extend from the front to the rear of the upper part of the box. To the underside of the seat are attached two 45 racks, one near each end of the same, (the further one only is shown in the drawing at r.) Below the seat and extending from side to side, is a shaft S to which under each rack is a toothed quadrant Q working into the 50 racks. The shaft S is operated by a lever L, attached near the off end thereof, so as to be conveniently operated by the right-hand of

the driver. The lever moves in a slot D along the upper edge of the arm of the seat, being held by stop-notches a, b, c, in the 55 proper position for the disposition of the seat, when in the notch a holding the same as far back as it can be moved, when in c as far forward, and when in b in the proper position for the disposition of the load when 60 traveling on level ground. When moving on rising ground the lever is to be thrown forward, by which the load will be brought directly above the axle. When moving down descending ground the lever is to be thrown 65 back by which the same result will be effected and the load maintained directly over the axle, as shown in Fig. 2 where the block lives represent the gig on an ascending grade, with the seat thrown back, and the red lines, the gig 70 on a descending grade, each grade with the seat thrown forward. A B the line perpendicular to the axis of the wheel. It will be seen that in the different positions the point C, assumed to be the center of gravity of the 75 load is directly in the line A, B. The advantage of this arrangement in relieving the horse from the annoyance and inconvenience of a load varying with every inequality of the ground, will be appreciated by every one 80 practised in the use of animals of burden, with loaded carriages.

I claim—

The method of adjusting the load carried in two wheeled vehicles, so as to keep the 85 pressure upon the animal drawing the same, equal or nearly so, whether the carriage be moving upon level or uneven ground, by shifting the seat, or upper body backward or forward using an axis with toothed quadrants operating upon toothed racks, attached underneath said seat or body, (or by the use 90 of any mechanical equivalent.) Said axis being maneuvered by a lever which passes up through the arm of the seat or upper body, 95 substantially as set forth in the within specification the said mechanical apparatus being in combination with the carriage body and seat.

GEORGE R. COMSTOCK.
